KNIFE

Louis V. Nigro, Chelsea, Mass., assignor to The Gillette Company, Boston, Mass., a corporation of Delaware

Application October 13, 1958, Serial No. 52,951

Term of patent 14 years

(Cl. D22—3)

Fig. 1

Fig. 3

Fig. 1 is a side elevational view of a knife showing my new design, the side opposite thereto being substantially similar in appearance;

Fig. 2 is a top view; and

Fig. 3 is a bottom view.

The essential features of the design reside in the portion shown in solid lines on the drawing.

I claim:

The ornamental design for a knife, as shown and described.
